UNITED STATES PATENT OFFICE

169,628

COMBINATION PROJECTOR AND
PHONOGRAPH

Robert H. Larson, Batavia, Ill., assignor to Du
Kane Corporation, St. Charles, Ill., a corpora-
tion of Illinois

Application February 8, 1952, Serial No. 18,439

Term of patent 14 years

(Cl. D61—1)

To all whom it may concern:

Be it known that I, Robert H. Larson, a citizen of the United States, residing at Batavia, in the county of Kane and State of Illinois, have invented a new, original, and ornamental Design for a Combination Projector and Phonograph, of which the following is a specification, reference being had to the accompanying drawings, forming part hereof.

Fig. 1 is a perspective view of a combination projector and phonograph embodying my new design with the turntable thereof shown in the storage position;

Fig. 2 is a side elevational view thereof with the turntable in operable position;

Fig. 3 is a front elevational view thereof without the turntable;

Fig. 4 is a fragmentary rear perspective view thereof;

Fig. 5 is a top plan view thereof with the turntable in operable position; and

Fig. 6 is a side elevational view thereof as seen opposite Fig. 2.

I claim:

The ornamental design for a combination projector and phonograph, as shown.

ROBERT H. LARSON.
